By H. J. Fisher, A.I.T.Y.

UNITED STATES PATENT OFFICE.

HENRY J. LUFF, OF CLEVELAND, OHIO.

WALL CLEAN-OUT AND BACK-VENT FITTING.

SPECIFICATION forming part of Letters Patent No. 783,586, dated February 28, 1905.

Application filed February 7, 1903. Serial No. 142,346.

To all whom it may concern:

Be it known that I, HENRY J. LUFF, a citizen of the United States, residing at Cleveland, in the county of Cuyahoga and State of Ohio, have invented new and useful Improvements in Wall Clean-Out and Back-Vent Fittings; and I do declare that the following is a full, clear, and exact description of the invention, which will enable others skilled in the art to which it appertains to make and use the same.

My invention relates to a wall clean-out and back-vent fitting for sink waste-water connections; and the object of the invention more especially is to provide means for facilitating the cleansing of the pipes and other parts in sink connections which are back of the trap therein.

It is well known that greasy deposits in waste-pipes from kitchen-sinks are not only constantly and inevitably occurring, but in time such deposits completely clog and fill the waste-passage, so that it becomes completely closed. Sometimes the accumulations gather above and in the air-vent so as to completely close said vent, and thus cause the sink-trap to siphon, which is most deleterious to health when it occurs, because of the opening it affords for the entrance of poisonous sewer-gases. Furthermore, the old-style sink connections were devoid of such construction as would facilitate or make easy or even practicable the cleansing of the said connections when this became necessary, and hence the present invention. By my invention an opening is provided immediately at the place of danger, whereby a plumber particularly can quickly and effectually deal with the trouble and remove all foreign matter and restore the parts to operating position with small labor and expense.

To these several ends the invention consists in the construction and combination of parts, substantially as shown and described, and particularly pointed out in the claims.

In the accompanying drawings, Figure 1 is a cross-sectional elevation of a sink-basin and a plan elevation of the waste-pipe and vent connection therewith. Fig. 2 is an enlarged front elevation of the fitting for the back-

vent and wall clean-out with a portion of the 50 cap thereon broken away to show internal constructions; and Fig. 3 is a vertical sectional elevation of said fitting on line xx , Fig. 2.

As thus shown, A represents a sink-basin, and B the waste-pipe therefor, including trap 55 2 and coupling pipe or section 3, having a threaded coupling or union with the extremity of trap 2. The other end has a threaded connection with boss 4 on cap C, screwed into a relatively large opening in the front of the 60 fitting D. In use the said fitting rests within the wall E, behind the sink, and I plan to bring the face of cap C about flush with the finished surface of said wall, so as to maintain appearances consistent with the other 65 open-plumbing effects. Structurally and internally the upper open end 6, constituting the vent portion of this fitting, begins practically at the substantially transverse line 7, which, it will be observed, is above the upper portion 70 of the inlet through cap C and especially above the inlet through pipe 3 in said cap. This is a very important feature in my construction, because it carries the said inlet so far below the mouth of the vent at 7 that 75 there is no possibility practically of the water splashing up into said vent, and thereby depositing adhesive matter and gradually filling up said vent-passage, as formerly. Then, again, it will be noticed that the mouth proper 80 of the vent lying, say, between points d and d' , lies at an angle of about forty-five degrees to the face of the front opening in fitting D, so that this part of the vent is within easy access if for any reason it should become clogged 85 and require cleansing; but the bowl 8 of the fitting is so constructed and the outlet downward therefrom is so ample that water passes directly down as it flows in and there is no opportunity for backing of the water into the 90 vent. At the most this cannot occur until the down-pipe is practically filled up, and this fact will at once disclose itself to the sink. Then removing the large face-cap C the whole 95 interior of fitting is laid open, as well as its up and down extremities or portions 6 and 9.

Cap C is preferably provided with an inner hood or extension 10 opposite its central open-

ing to deflect the water downward and more effectually guard against any matter splashing upward into the vent-opening.

It will be seen that the trap 2 and wall-fitting D are wholly separate and distinct from each other and that the trap is essentially of a self-cleansing variety, being preferably of the so-called **S** pattern. Hence there is no clogging possible therein. Then it is connected with said wall-fitting by means of a removable pipe-joint 3, supported on and connected with trap 2, so that when cleansing of the fitting is to occur said joint is first removed and then the cap C, whereupon the whole interior of the fitting is laid open for cleansing.

What I claim is—

1. A sanitary fitting for waste water from sinks and the like consisting of a hollow body having a vent-opening in its top and a water-outlet at its bottom constructed each to make pipe connections and provided with a circular threaded opening at its front, in combination with a removable cap closing said threaded opening and constructed with a threaded open-

ing at its middle and having a downwardly-curved deflector on its back extending substantially across beneath the said vent-opening and wholly apart from the wall thereof, substantially as described.

2. In waste-water connections for sinks and the like, a trap of substantially the **S** pattern, in combination with a back vent-wall fitting constructed top and bottom to make up and down pipe connections and having a front opening, a cap to close said opening having a curved deflector on its back extending across the space beneath the vent-outlet from said fitting and apart from the wall thereof, and a detachable pipe-joint 3 connecting said trap and cap, whereby said joint and cap can be removed when said fitting requires cleansing, substantially as described.

Witness my hand to the foregoing specification this 31st day of January, 1903.

HENRY J. LUFF.
